ACTIVITY TOY

Timothy J. McHugh, Eastchester, N.Y.

Filed May 6, 1960, Ser. No. 60,481

Term of patent 14 years

(Cl. D34—15)

Fig. 1 is a front elevation of an activity toy, showing my new design.

Fig. 2 is a plan view of the activity toy shown in Fig. 1.

Fig. 3 is a side elevation of the activity toy shown in Fig. 1.

The dominant features of my design reside in the portions shown in full lines.

I claim:

The ornamental design for an activity toy, as shown and described.
